DISPENSING DEVICE

Elra F. Howe, Chicago, Ill.

Application October 30, 1952, Serial No. 317,796

5 Claims. (Cl. 15—137)

This invention relates to a dispensing device and more particularly to a dispensing device particularly adapted to dispense measured quantities of a plastic material.

It is the general object of this invention to produce a new and improved dispensing device of the character described.

While it will be clear to those skilled in the art that the dispensing device of this invention has many applications, it has been found to be particularly useful when used for dispensing "dope" used by plumbers for coating the threads at the end of a pipe before screwing the pipe into a union or other threaded fitting. It has heretofore been common practice for a plumber to carry a can of dope as he proceeds with his work and to dispense the same from the can by means of a stick or paddle which is used to apply the material to the threads of the pipe. The particular plastic material or dope used has a tendency to dry out if allowed to remain for any length of time in an open container and the previous methods of applying the material have been wasteful and in many cases quite messy.

According to this invention, however, there is provided a dispensing device which may be used for dispensing desired quantities of such pipe fitting material. One of the features of the present invention is the provision of a dispensing device which is simple to operate and will dispense desired quantities of plastic material without waste or mess. Another feature of the invention is the provision of a dispensing device which retains a supply of plastic dope or material in an air free chamber so that the same may be used over long periods of time without drying up.

A more specific feature of the invention is the provision of a dispensing device having a chamber adapted to contain a supply of the plastic material together with means in the chamber for producing an expelling pressure on the material and means accessible exteriorly of the chamber for operating the pressure producing means, with the last-named operating means being provided with a flow passageway through which the expelled material may travel to the exterior of the chamber for application to pipe threads.

Another feature of the invention is the provision of a casing having a cylinder therein in which is located a piston movable to apply an expelling pressure on a supply of plastic material in the cylinder, with the piston being provided with thread means engaging threads on a hollow rod extending axially through the cylinder, the rod having a portion exterior of the cylinder provided with a plurality of slits through which the material is extruded when the rod is rotated to move the piston in the cylinder.

A further feature of the invention is to provide a dispensing device of the type described in the preceding paragraph wherein the cylinder is provided with a readily removable closure so that the same may be resupplied with the material and in which the orifices through which

2

the material is finally extruded may be closed by a sliding sleeve which serves to cut off or remove any excess material on the exterior side of the orifices and to maintain the orifices closed when the device is not in use to prevent drying out of the plastic material.

Another feature of the invention is the provision of distributing means for the extruded material so that the same may be evenly spread on a pipe joint, with such distributing means taking the form of a brush having bristle portions immediately adjacent the extrusion orifices.

Other and further features of the invention will be readily apparent from the following description and drawing, in which:

15 Fig. 1 is a side elevation of the dispensing device illustrating the invention;

Fig. 2 is a vertical section taken through the device shown in Fig. 1;

Fig. 3 is a horizontal section along line 3—3 of Fig. 20 1; and

Fig. 4 is a horizontal section along line 4—4 of Fig. 1.

While this invention is susceptible of embodiments in many different forms, there is shown in the drawing and will herein be described in detail one specific embodiment, with the understanding that the present disclosure is to be considered as an exemplification of the principles of the invention and is not intended to limit the invention to the embodiment illustrated. The scope of the invention will be pointed out in the appended claims.

30 Referring now to the drawing, there is shown a casing 10 having a cylinder 11 formed therein, the bottom end of which is closed by a closure member 12. Inasmuch as the chamber or cylinder 11 is adapted to contain a supply of the plastic material to be dispensed by the device, the closure member 12 is mounted to be readily removable from the casing so that the cylinder 11 may be resupplied with material from time to time as is necessary. To this end the lower end of the casing 10 is provided with an exteriorly threaded enlarged

40 portion 13. A retaining member 14 is provided with threads engaging the threads on the flange 13 and with an inwardly directed annular portion 15 adapted to seat in an annular notch 16 formed in the bottom of the closure member 12. Rotation of the retaining member 45 14 serves to draw the closure member 12 up against an annular gasket 17 positioned between the flange 13 and the inner face of the closure member. Simply by rotating the retaining ring 14 the closure may be removed to refill the cylinder.

50 The closure member 12 is provided with an integral boss 20 at its center which is formed with a cylindrical recess 21 rotatably supporting one end of a rod 22 which extends axially through the center of the cylinder 11. The portion 23 of the rod within the cylinder 11 is threaded, as illustrated, with the threads engaging internal threads formed on a backing member 24 forming a part of a piston 25 which is movable in the cylinder. The piston 25 is provided with a cover plate 26 secured to the backing member by means of the screws 27 and simultaneously

55 clamping therebetween a resilient annular gasket member 28. The gasket member is provided with inturned outer portions 29 which engage the walls of the cylinder and provide a substantially air-tight fit therebetween.

60 A step 30 is formed on the rod portion 22 within the cylinder adjacent the upper end thereon on which step is seated a washer 31 adapted to abut against the upper end of the casing to prevent longitudinal movement of the rod. Secured to the outer portion of the casing is a bearing member 32 having an opening through which a second portion 33 of the rod extends, with the second portion being exterior of the cylinder 11.

65 70

The rod 22 is hollow, as indicated at 35, and the portion 23 thereof within the cylinder is provided with a plurality of openings 36 establishing communication between the interior of the cylinder and the hollow of the rod. The exterior portion 33 of the rod is provided adjacent its outer end with a plurality of slit-like orifices 37 through which the material is extruded. A fitting 38 is fixed to the outer end of the rod and is provided with an internally threaded opening adapted to receive a screw device 39 serving to close the outer end of the rod. The provision of the screw device 39 permits ready cleaning of the hollow in the rod and should the same become clogged after a relatively long period of use, the screw 39 may be removed and the hollow of the rod cleaned out in a suitable manner.

For the purpose of rotating the rod 22 and thus to cause movement of the piston 25, the exterior portion 33 of the rod is provided with a manually rotatable disk 40 having an integral boss portion 41 provided with a set screw 42 adapted to be tightened against the rod portion 33 so that rotation of the disk produces rotation of the rod and hence expelling movement of the piston. The device is so proportioned that by holding the casing 10 in one hand the thumb and forefinger of that hand can readily reach the disk 40 to rotate the same and hence extrude plastic material from the slits 37. Thus the device can be operated simply with one hand while the other hand is occupied in holding the pipe or joint.

When the rod is rotated and the cylinder 11 is filled with plastic material the piston 25 exhibits no tendency to rotate with the rod, the plastic friction with the material in the cylinder being quite capable of preventing such rotation.

Preferably the fitting 38 is provided with a second opening 50 extending diametrically through the screw receiving opening into which may be inserted an outer portion 51a of a brush 51 having a wire core 51b which is spiraled around the outer end of the rod and provided with a plurality of bristles 51c positioned immediately adjacent the orifices 37 so as to receive material as the same is extruded therefrom. The brush serves as a distributing means to distribute the material over the pipe fitting, threads and the like.

In order to prevent the material within the hollow of the rod from drying out, particularly in the area immediately adjacent the orifices 37, there is provided a sleeve 55 slideable on the exterior portion of the rod and having a length at least equal to the length of the orifices 37. The sleeve may be slid along the outer portion of the rod from the position shown in Figs. 1 and 2, wherein the orifices 37 are uncovered, outwardly to a position radially inwardly of, or under, brush bristles 51c where in the orifices 37 are covered. As brush 51 is secured only at the outer portion 51a such positioning is effectively unimpeded by the brush. Such outward movement of the sleeve accomplishes two purposes. In the first place it cuts off any strings or portions of material extruded out of the orifices 37 and thus, in effect, cleans the outer end of the rod, and secondly when in position covering the orifices protects the material therein from the drying action of air and thus preserves the plasticity of the material even though the device is not used again for some time.

It is believed to be apparent from the foregoing that the dispensing device of this invention is not only simple and convenient to use, but also is relatively inexpensive to manufacture and if constructed in accordance with this invention will provide a dispensing device which may efficiently and effectively be used for dispensing many forms of materials.

I claim:

1. In a device for dispensing a plastic material including a hollow casing adapted to contain a supply of the material, a hollow rod extending outwardly from the casing and having an outer end, with at least one orifice spaced from said casing and opening through the exterior of the rod between said end and said casing, with the hollow of the rod being in communication with the interior of the casing and said orifice for conducting material from said casing, and means for forcing material through said rod hollow and said orifice, means of the character described, comprising: a brush constructed and arranged to overlie said orifice and to extend radially outwardly along said rod to receive material discharged therethrough, and fixedly secured to said rod exteriorly of said casing; and a closure member carried exteriorly on said rod and movable thereon between said brush and said rod alternatively to uncover and cover said orifice.
2. The device of claim 1 wherein said closure member comprises a tubular sleeve on the rod reciprocable relative to said rod and said brush.
3. The device of claim 2 wherein the sleeve is longitudinally reciprocable on the rod and the brush extends longitudinally of the rod less than the length thereof and is secured to the rod at one end only.
4. The device of claim 3 wherein said brush is secured at the outer end only.
5. The device of claim 1 wherein the orifice is elongated longitudinally of the rod and the brush extends at least the length thereof.
